2 Claims

ABSTRACT OF THE DISCLOSURE

A table having a stationary frame composed of a pair of end panels connected by a fixed frame of less width than the panels. A leaf-supporting frame is attached by a vertical pivot to the inside face of one of the panels at one side of the fixed frame and a similar leaf-supporting frame is similarly pivoted to the said panel at the opposite side of the fixed frame. Each of the leaf-supporting panels has a pivotally attached leg-bearing frame, and the leaf-supporting and leg-bearing frames are capable of movement to a housed position between the panels when leaves attached to the fixed frame are swung downwardly, said leaves being supported by the leaf-supporting frames and by the leg-bearing frames when the leaf-supporting and leg-bearing frames are swung outwardly from the fixed frame and said panels are disposed horizontally and rest upon said frames.

The structure in question is constituted by two elements in the form of a frame, articulated to one another in such a manner that it is possible to collapse one against the other. One of the said elements is in turn articulated to a lateral element of the fixed framework of the table. The other element is consequently joined to the said fixed frame by means of the intermediate element. Both folding frameworks are equipped with interior projecting pieces which are supported on the floor in the manner of legs, either directly or by means of an adjustable wheel or caster.

Both the frameworks have appropriate dimensions so that on collapsing them against the fixed framework, the collapsible tabletop, articulated at the upper horizontal edge of the fixed framework, covers both the folded frames, and on these frames being unfolded they support the said collapsible tabletop in a horizontal position.

The said fixed framework can articulate two collapsible tabletops on each side. Likewise, it can form part of a suitable piece of furniture which can incorporate other folding elements, identical with or distinct from that which is the subject of the present invention.

In order to enable the invention to be better understood, in the annexed drawings, which complement the present exposition, there is shown a practical form for its industrial embodiment which is included with a merely informative character, and consequently is not limitative of the invention.

In the said drawings, FIGS. 1, 2 and 3 show the structure of a table in accordance with the invention in an unfolded, semiunfolded and completely folded position, respectively, the tabletop being omitted for the sake of greater clarity.

FIGS. 4, 5 and 6 show the same table, now including the tabletop in the completely unfolded position, with one single tabletop unfolded, and both tabletops collapsed.

FIGS. 7, 8 and 9 show, in an arrangement similar to that of FIGS. 1, 2 and 3, a structure in accordance with the invention but corresponding to another form of embodiment.

FIGS. 10, 11 and 12 show the same table as that represented in FIGS. 7, 8 and 9, complete with both tabletops.

2

FIG. 13 shows a variant of embodiment of the same invention, applied to a piece of office furniture.

As is shown in FIGS. 1 to 6, the structure of the table is constituted by a fixed framework formed by two lateral elements (FIG. 1) joined by a frame 2; in one of the said lateral elements, near the edge and at the inner face, there is articulated, by means of hinges, an element 3 in the form of a frame which by its other lateral part is articulated to another similar framework 4, by means of the hinges 5. The said articulation 5 is prolonged below the frame, following the coincidence between an inferior prolongation of the frame 3, which operates as a leg, and another similar prolongation of the frame 4, which in turn, has another leg at its other end.

15 The said fixed framework articulates a structure such as that described on each side, when a folding table with two collapsible tabletops is involved. The said tabletops are articulated at the corresponding edge of the small intermediate tabletop 7 which joins both the lateral elements 1 of the fixed framework.

20 As is clearly shown in FIGS. 1 to 3, the supporting structure for the tabletops can be situated in the completely unfolded position, the two frameworks 3 and 4 forming a right angle, in such a manner that a support with four supporting elements is constituted for each tabletop. In the said position the check-pieces 8 limit and fix the position of the folding structure. In the said position, both the frameworks 3 and 4 are collapsed one against the other, and the complex is collapsed against the frame 2 of the fixed framework in such a manner that the edges of the lateral elements 1 do not project beyond the external superimposed framework 3.

25 Consequently the corresponding tabletop 6 conceals the said folded complex, which is housed in the interior of the recess so formed.

30 FIG. 13 shows a structure such as that described, coupled to the lateral elements 13, of a piece of furniture 12 equipped with drawers. This piece of furniture consequently acts as the fixed framework, and is equipped with an upper tabletop and collapsible lids or tabletops, which are not represented in the drawings.

35 The folding frameworks can adopt other forms, such as, for example, those represented in FIGS. 7 to 12. In this case, the said frameworks are formed by an upper cross-piece which joins two legs which, in the end framework 11 are equal, and in the framework 10 are of different lengths. In the framework 10, the external leg is equal to the legs of the framework 11, to one of which it is articulated, and the inner leg 9, which is shorter, is articulated to the fixed framework.

40 The folding and unfolding, as well as the arrangement of the tabletops, are identical with the form which has been described above.

45 Evidently a structure such as that described is capable, in any one of its variants, of forming part of numerous pieces of furniture, especially of pieces of furniture of the unit type, and can likewise be combined with any folding structure, equal to or different from that described.

Having sufficiently described the nature of the invention, together with an example of its practical embodiment, it only remains to add that in the complex and parts described it is possible to introduce changes of material, form and arrangement of the elements, provided that such alterations do not affect the essence of the invention.

50 I claim:

55 1. A foldable table structure comprising: a stationary frame including a pair of spaced-apart panels, a bracing frame extending between and secured to the panels, said bracing frame being of less width than the width of each panel whereby portions of the panels project laterally

beyond the sides of the bracing frame to thereby provide storage spacing between the side edges of the panels and the bracing frame, a leaf support including a first leaf-supporting frame attached by a vertical pivot to the inside face of one of the panels, a second leaf-supporting frame pivotally attached to the outer end of the first leaf-supporting frame whereby the second frame can be swung to dispose it at right angles to the first leaf-supporting frame, the second frame having legs by which it can rest on the floor, the second leaf-supporting frame being swingable on its pivot to bring it flatly against the inside of the first leaf-supporting frame and the two leaf-supporting frames being swingable to bring them into one of the storage spaces to one side of the bracing frame, a cross piece extending between and connecting the tops of the panels, and leaves attached on horizontal pivots to the cross piece, one of said leaves being horizontally disposed and supported by the leaf-supporting panels when said panels are extended out of the storage space and said leaves being downwardly dependent to cover and conceal the frames in the storage space when such frames are housed in at least one of such spaces.

2. A foldable table structure according to claim 1,

wherein one of the first leaf-supporting frames is attached to the panel at the opposite sides of the bracing frame, with each of the leaf-supporting frames and its attached second frame being capable of storage in each of the storage spaces, the second leaf-supporting frame in each of the supports being foldable in a manner to dispose it between the first frame and the bracing frame in the storage position of the support.
